(57) **CLAIM**

The ornamental design for a telescopic swimming and exercise device, as shown and described.

DESCRIPTION

FIG. 1 is a perspective view of a telescopic swimming and exercise device showing my new design in a collapsed storage position;

FIG. 2 is a side elevation view of FIG. 1;

FIG. 3 is a side elevation view of FIG. 2;

FIG. 4 is an enlarged left end elevation view of FIG. 1;

FIG. 5 is an enlarged right end elevation view of FIG. 1;

FIG. 6 is another perspective view of FIG. 1 in an extended in-use position;

FIG. 7 is a section view in the direction of arrows 7-7 in FIG. 6; and,

FIG. 8 is a view of the invention in FIG. 6 in use. The broken lines are for environmental purposes and do not form part of the claimed design.
